COMPRESSED CATHODE SUPPORT
STRUCTURE

Percy L. Spencer, West Newton, Mass., assignor
to Raytheon Manufacturing Company, Newton,
Mass., a corporation of Delaware

Application May 19, 1948, Serial No. 27,931

9 Claims. (Cl. 250—27.5)

1

This invention relates to cathode structures, and more particularly to an indirectly-heated cathode structure particularly useful in electron discharge devices of the so-called magnetron type.

For modern, relatively high-power, continuous-wave electron discharge devices of the general character above referred to, as described in my Patent No. 2,473,550, issued June 21, 1949, and in the patent to Hanson No. 2,477,601, issued August 2, 1949, it has been found desirable to utilize, for the electron-emissive member of such devices, a solid sleeve of compressed, intimately admixed, powdered material. Such a sleeve may be formed by molding, as described in the aforesaid Hanson application.

Solid cathode sleeves of the aforementioned type have been found, however, to be of a rather fragile nature, such that they will not withstand, to a very great degree, sudden changes in temperature, but instead will very often crack or break in a rather short time when subjected to such temperature changes. In other words, such sleeves are sensitive or responsive to heat shock.

In many cases, it is desirable to utilize for magnetrons a cathode of the indirectly-heated type. If it is attempted to utilize a solid cathode sleeve of the aforesaid rather fragile type in a conventional indirectly-heated structure, serious difficulties arise, due to the fragile nature and extreme sensitivity to heat shock of such a sleeve. It has been found, according to this invention, that if such a powdered sleeve is supported only at its ends and a heater is positioned therein, in the conventional manner, the cathode is still rather short-lived, due to the fragility of the sleeve or to the limited area, and therefore the relative weakness, of the joint between the sleeve and the support.

Accordingly, an object of this invention is to devise an indirectly-heated cathode structure utilizing a molded powdered sleeve, in which the above-described difficulties are overcome.

Another object is to devise a means for using a solid cathode sleeve of a fragile type, in an indirectly-heated cathode structure, in an effective and efficient manner, such that the structure has a long usable life.

A further object is to provide a cathode structure wherein a fragile cathode sleeve is supported in a rigid manner throughout its length, and yet in which the support permits substantially unimpeded expansion and contraction of the said sleeve.

A still further object is to devise a cathode sleeve 55 and which are located in the central

2

structure for magnetrons, the emissive portion of which operates at a rather elevated temperature, and yet in which the portions of the supports beyond the ends of the said emissive portion remain cool, relative to the temperature of said emissive portion.

The foregoing and other objects of the invention will be best understood from the following description of an exemplification thereof, reference being had to the accompanying drawing, wherein:

Fig. 1 is an elevation of a cathode sleeve of the type utilized in this invention;

Fig. 2 is a vertical section through a cathode structure according to this invention, certain parts thereof being shown in elevation;

Fig. 3 is an elevation of the upper portion of the structure of Fig. 2, on an enlarged scale;

Fig. 4 is a horizontal section taken on line 20 4—4 of Fig. 2, looking in the direction of the arrows; and

Fig. 5 is a horizontal section taken on line 5—5 of Fig. 2, looking in the direction of the arrows.

Referring now to the drawing, reference number 10 indicates a cylindrical sleeve of compressed, intimately admixed, powdered thoria (thorium oxide) and a powdered refractory metal, metal compound, metal alloy, or mixture of metals, such as molybdenum, molybdenum carbide, molybdenum-cobalt, molybdenum-nickel, tungsten, tungsten carbide, tungsten-cobalt, or tungsten-nickel. Such sleeves are described and claimed per se in the above-identified copending patents of Hanson and Spencer, and may be fabricated as disclosed in the aforesaid Hanson application. Sleeve 10, when heated to a temperature of thermionic emission, emits electrons copiously, and is particularly suitable for use as an emitter in electron discharge devices of the magnetron type.

In order to position and rigidly support sleeve 10, said sleeve is slipped over a thin cylindrical metallic supporting sleeve 11 which is made of a material capable of withstanding high temperatures, such as molybdenum for example. The cathode sleeve 10 is rigidly secured, as by brazing with platinum or with molybdenum powder, to the outer surface of the central portion of supporting sleeve 11. Sleeve 11 has a length substantially in excess of that of sleeve 10, and the former is provided with a plurality, here shown as eight, of equally-spaced parallel longitudinally-extending slots 12, which have a length somewhat greater than the length of cathode

portion of sleeve 11 which is covered by sleeve 10 in the assembled structure. At both its upper and lower ends, each slot 12 communicates with a corresponding transversely-extending slot 13, so that each of the combined slots 12-13 is in the shape of the letter I. The center lines of all of the upper transverse slots 13 lie in a common horizontal plane, as do also the center lines of all of the lower transverse slots 13, and the lengths of all of the said slots 13 are made such as to leave only narrow areas of metal between adjacent slots, as shown. Supporting member 11, with the slots 12-13 therein, is preferably formed by being stamped out of sheet material and afterwards being bent into cylindrical shape, as indicated by the longitudinal seam 14 indicated on the drawings.

Slots 12 extend throughout the length of the area of attachment of cathode sleeve 10 to supporting sleeve 11, sleeve 10 being secured rigidly to sleeve 11 in said area of attachment. Slots 12 extend entirely through the thickness of sleeve 11 and are spaced from each other, leaving separate metal strips between adjacent slots 12. Such slots provide a certain resilience for the central portion of supporting sleeve 11, to which portion cathode sleeve 10 is secured, such as to allow for differential expansion between the material of sleeve 10 and the material of sleeve 11. By such structure, the cathode sleeve 10 can expand and contract freely in response to temperature changes without strains being produced therein, while at the same time said cathode sleeve is rigidly attached and supported by sleeve 11 at all times, since such differential expansion between sleeves 10 and 11 is provided for by slots 12. Undue strains in sleeve 10 are thus prevented, and at the same time the joint between sleeves 10 and 11 is substantially unaffected by temperature changes, thus increasing the life of the cathode.

The cathode sleeve 10 is heated to the temperature of thermionic emission by the means to be hereinafter described, which temperature is rather high, and it is desirable, for many reasons, to prevent the end portions of supporting member 11 from being heated to this high temperature. The transverse slots 13, at each end of the central portion of sleeve or member 11, provide a heat choke, heat shield, or heat interrupter to minimize the conduction of heat from the heated central portion of sleeve 11, to the end portions of said sleeve. Thus, as shown in Fig. 4, there are only very narrow metallic areas between adjacent slots 13, the greater part of the horizontal cross-section through slots 13 being insulating air space. Since the cross-section of heat-conducting metal between the end and central portions of supporting sleeve 11 is in this way held to an absolute minimum, the conduction of heat from the central to the end portions of said sleeve is limited to a very small amount, so that said end portions remain cool relative to said central portion, when said central portion is heated for electron emission.

A hollow cylindrical metallic sleeve 15 is fastened, as by welding or brazing, to the lower end of supporting sleeve 11, the upper end of sleeve 15 being provided with an internal shoulder on which rests the lower end of sleeve 11. Sleeve 15 is made of a metal, such as Kovar, which is commonly used for sealing to glass, and a hollow glass insulating bead 16 is fused at its upper end to the lower end of sleeve 15. The lower end of bead 16 is in turn fused to the upper end of a

second metallic sleeve 17 which is also preferably made of Kovar. In order to secure the lower end of an elongated rigid supporting conductor 18 centrally or axially of members 11, 15, 16 and 17, a dished metallic member 19, having an aperture in its center through which conductor 18 passes and in which said conductor is secured, is fastened at its outer edge, as by welding or brazing, to the lower end of member 17. Thus, conductor 18 is mounted centrally of sleeves 11 and 15 and is insulated therefrom by bead 16.

A heater wire 20, of tungsten or other suitable material, fashioned in the form of a helix, has its lower end rigidly secured centrally of sleeve 11 to the upper end of conductor 18, which upper end is located a little above the lower end of sleeve 11. Heater 20 therefore is mounted centrally inside supporting sleeve 11, and the coils thereof extend somewhat beyond the upper and lower end surfaces of cathode sleeve 10. In order to secure the upper end of heater 20 in position, an imperforate metallic cap or cover 21, having a central outwardly-extending projection 21a thereon, is secured to the upper end of sleeve 11 in any suitable manner. The upper end of heater wire 20 is bent toward the center of the coil thereof, as shown, and is welded to the inside or lower surface of projection 21a, this projection being provided for easy and convenient welding. In this way, by rigid attachment to conductor 18 and to cover member 21, heater 20 is held in position centrally of sleeve 11.

A lead wire 22 is electrically connected to sleeve 15, and another lead wire 23 is electrically connected to conductor 18. When a suitable source of heater voltage, here represented by a battery 24, is connected between leads 22 and 23, current flows through lead 23, conductor 18, heater 20, cap 21, sleeve 11, sleeve 15, and lead 22, the current passing through heater 20 being converted to heat therein which heats cathode sleeve 10 to the temperature of thermionic emission. Due to the high resistance of sleeve 10, only a very small amount of heating current will flow through said sleeve.

This completes the description of the aforesaid exemplification of the present invention. It will be noted that there has been provided an effective and easily-fabricated cathode structure having a longer life than generally available prior to this invention, and one which is suitable for use in high-power continuous-wave magnetrons.

Of course, it is to be understood that this invention is not limited to the particular details as described above, as many equivalents will suggest themselves to those skilled in the art. It is accordingly desired that the appended claims be given a broad interpretation commensurate with the scope of this invention within the art.

What is claimed is:

1. A cathode structure comprising a supporting sleeve of thin sheet refractory metal, a compressed sleeve of powdered electron-emissive material surrounding and secured to said supporting sleeve, and heater means mounted inside said supporting sleeve.

2. A cathode structure comprising a metallic supporting sleeve, a compressed sleeve of powdered electron-emissive material surrounding and secured to said supporting sleeve, said supporting sleeve having a plurality of slots in the portion of said metallic sleeve surrounded by said compressed sleeve to permit differential expansion of said two sleeves, and heater means positioned inside said supporting sleeve.

3. A cathode structure comprising an elongated metallic supporting sleeve, a compressed sleeve of powdered electron-emissive material surrounding and secured to the central portion of said supporting sleeve, said supporting sleeve being provided with openings for inhibiting the flow of heat from said central portion to the two end portions thereof, and means positioned inside said supporting sleeve for heating the central portion thereof and thereby also said compressed sleeve.

4. A cathode structure comprising a thin-walled supporting sleeve of molybdenum, a compressed sleeve of powdered thoria and molybdenum surrounding and secured to said supporting sleeve, and heater means positioned inside said supporting sleeve.

5. A cathode structure comprising an elongated metallic supporting sleeve, a compressed sleeve of powdered electron-emissive material surrounding and secured to the central portion of said supporting sleeve, said supporting sleeve being provided with openings for inhibiting the flow of heat from said central portion to the two end portions thereof and being further provided with slots permitting differential expansion of said two sleeves, and means positioned inside said supporting sleeve for heating the central portion thereof and thereby also said compressed sleeve.

6. A cathode structure comprising an elongated metallic supporting sleeve, a compressed sleeve of powdered electron-emissive material surrounding and secured to the central portion of said supporting sleeve, said supporting sleeve being provided with a plurality of longitudinally-extending slots in the central portion thereof for permitting differential expansion of said two sleeves, and heater means positioned inside said supporting sleeve.

7. A cathode structure comprising a thin-walled supporting sleeve of molybdenum, a compressed sleeve of powdered thoria and molybdenum surrounding and secured to said supporting sleeve, said supporting sleeve being provided with slots permitting differential expansion of said two sleeves, and heater means positioned inside said supporting sleeve.

8. A cathode structure comprising an elongated thin-walled supporting sleeve of molybdenum, a

compressed sleeve of powdered thoria and molybdenum surrounding and secured to the central portion of said supporting sleeve, said supporting sleeve being provided with slots permitting differential expansion of said two sleeves and being further provided with means for inhibiting the flow of heat from said central portion to the two end portions thereof, and means positioned inside said supporting sleeve for heating the central portion thereof and thereby also said compressed sleeve.

9. A cathode structure comprising a metallic supporting sleeve, a compressed sleeve of powdered electron-emissive material surrounding and secured to said supporting sleeve, said supporting sleeve being provided with slots in the portion of said metallic sleeve surrounded by said compressed sleeve thereby permitting differential expansion of said two sleeves, a stiff supporting conductor mounted substantially axially of said supporting sleeve and insulated therefrom, and a coiled heater mounted substantially concentrically of said supporting sleeve, said heater having one end secured and electrically connected to said conductor and its opposite end secured and electrically connected to said supporting sleeve.
